US00D890330S

(12) **United States Design Patent** (10) Patent No.: **US D890,330 S**
(45) Date of Patent: ** *Jul. 14, 2020

(54) **INTRANASAL DRUG DELIVERY DEVICE**

(71) Applicant: **Janssen Pharmaceutica NV**, Beerse (BE)

(72) Inventors: **Jungli Wang**, San Jose, CA (US); **Michael Cannamela**, Atlantic Highlands, NJ (US); **Hong Yan**, Pleasanton, CA (US); **Rochelle Kleinberg**, New York, NY (US)

(73) Assignee: **Janssen Pharmaceutica NV**, Beerse (BE)

(*) Notice: This patent is subject to a terminal disclaimer.

(**) Term: **15 Years**

(21) Appl. No.: **29/703,229**

(22) Filed: **Aug. 26, 2019**

CLAIM

The ornamental design for an intranasal drug delivery device, as shown and described.

DESCRIPTION

FIG. 1 is a top perspective view of an intranasal drug delivery device, showing our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof; and,

FIG. 8 is a bottom perspective view thereof.

The features shown in broken lines represent portions of the intranasal drug delivery device which form no part of the claimed design.

1 Claim, 7 Drawing Sheets
